William H. Green & C. P. J. Clark, of West Meriden, Conn.

Assignors to

S. S. Clark of same place.

Letters Patent No. 1614, dated Augt. 5. 1862.

The schedule referred to in these Letters Patent and making part of the same.

To all whom it may concern:

Be it known that we, W. H. Green and P. J. Clark, of West Meriden, in the County of New Haven and State of Connecticut, have invented a new and original Design for a Lamp Bracket, and we do hereby declare that the following is a full clear and exact description of the same, reference being had to the accompanying drawings, making a part of this specification in which:

Figure 1. is a side elevation of a lamp bracket showing our design.

Figure 2. a horizontal section of the same, taken in the line α . α Figure 1.

Similar letters of reference indicate corresponding parts in the two Figures.

This invention relates to a new and original design for a bracket for holding lamps and which are secured to the walls of an apartment or any fixture therein.

The bracket has a curved arm A, with four concave sides α , which leave or form a corresponding number of projections β , one at each side and one at the top and bottom. The inner end of this arm is connected to a flat

Des 16 14

plate B, which is attached to the wall or fixture which holds the bracket. The arm A. has its concave side uppermost and is of semi circular form and supports a socket C, which receives the lamp. This socket is of basket form it being composed of upright bars c, curved outward at their upper parts, and forked or diverged at their upper ends and curved as shown at d, to form semi circular tops which cross each other at e, leaving a scalloped edge with tri lateral openings f, at the forks of the uprights and gothic arches g, between the upper parts of the bars c.

The outer curvature of the bars c, give a flaring form to the basket or socket C, and the bars c, are placed in the form of a circle, and they spring from a flat circular bottom Z, as shown in Figure 2.

The whole forms a neat and ornamental design for a lamp bracket the general appearance of which is shown in Figure 1.

Having thus described our invention what we claim as new and desire to secure by Letters Patent, is -

The general configuration of the parts herein shown and described to form a new and original design for a Lamp Bracket.
